UNITED STATES PATENT OFFICE

EARL S. CALDOR, OF NEW YORK, N. Y.

BATHING BRASSIÈRE

Application filed June 21, 1930. Serial No. 462,885.

The present invention relates to bathing brassières and consists in the combinations and arrangements of elements hereinafter described and particularly set forth in the accompanying claim.

The purpose of the invention is to provide an article of this character which embodies all of the desirable features of artistry and will give warmth to the wearer. The article employs the minimum number of parts in its manufacture and as a finished product is of the utmost simplicity.

A further purpose of the invention is to produce a bathing brassière which may be worn with the greatest degree of comfort and is of such design of construction that a reasonably large pocket device is provided for the carrying of a handkerchief or the like.

The invention is shown by way of illustration in the accompanying drawing, wherein:

Figure 1 is a perspective view of the brassière complete, and;

Figure 2 a top plan view thereof.

Referring to the construction in further detail the article consists of two similar non-stretchable and upstanding triangular pieces of fabric, e. g. woolen, 3 and 4, having for their greater portion substantially the outline of a triangle and along one side edge 5 each of said fabric portions has at its rear corner an appreciably long extended part as is clearly indicated in Figure 1. Thus, in the finished brassière each fabric portion is disposed to extend upwardly and rearwardly as shown, the triangular portions covering the breasts and the extended parts covering those parts of the body immediately in rear of the breast, so as to provide the maximum protection and warmth.

The two fabric portions are provided with plaits or darts and are united in overlapping relation at the front and there secured by a diagonal line of stitching 6 and along the bottom edge by a suitable tape 7. The binding tape 7 extends along the full lower marginal edge of the two fabric portions 3 and 4 and at their respective ends are connected with two strips of elastic tape 8 and 9 having

buttons 11 that are secured to the front tape portion 7 as shown.

The marginal side edges of the fabric portions 3 and 4 are similarly bound by tape straps 12 which extend for the full length thereof. And the overlapping of the front corner portions of the pieces 3 and 4 provides the pocket 13 to which access is had along the opening line 14 thereof. It will be understood, of course, the pocket is otherwise closed by the line of stitches 6 and the binding tape 7. The stitches 6 connect the diagonal edge of the inner corner portion to the outer corner portion and the diagonal edge of the outer corner portion is free of connection with the inner corner portion so as to provide the entrance 14 for the pocket.

In its application to the wearer the binding tape 7 together with the elastic tapes or cords 8 and 9 form the body encircling portion of the article and two similar shoulder straps 15 are provided. Each of these shoulder straps is of elastic material similar to the members 8 and 9, and connects with the fabric member at the top and rearwardly extending portion as indicated at 16 and 17 respectively.

It will be understood that the invention as herein disclosed is not limited to the details of construction shown and described as these may be varied without departing from the spirit of the invention as defined by the claim.

The fabric is so cut in the making of the article that all strains are on the bias thereof, thus giving maximum wear, and the marginal braid bindings take up all pulls to which the same is subjected.

What is claimed as new is:

A bathing brassière comprising warmth giving members having triangular breast covering portions and having elongated parts extending from the rear corners of the breast covering portions to cover those parts of the body immediately in rear of the breasts, a body encircling portion formed of a tape strip and elastic members connected at the respective ends thereof, the breast covering portions and their elongated parts being secured to and extending upwardly from the tape strip, the breast covering portions hav-

ing their front corners arranged in overlapping relation to provide a pocket, the lower edges of said front corners being secured to the tape strip and the diagonal edge of the 5 inner front corner being secured to the outer front corner to close the pocket, the diagonal edge of the outer front corner being free of connection with the inner front corner to provide an entrance for the pocket, tape strips 10 secured to the upper edges of the breast covering portions and their elongated parts, means for securing the elastic members detachably to the said first tape strip, and shoulder straps secured to the upper corners of 15 the breast covering portions and to the rear ends of the elongated parts of said portions.

In witness whereof, I have hereunto set my hand.

EARL S. CALDOR.
